UNITED STATES PATENT OFFICE.

BERNHARD D. BEIDERHASE, OF NEW YORK, N. Y.

DESIGN FOR TABLE-SPOONS.

Specification forming part of Design No. 5,876, dated May 28, 1872.

Specification describing a new and original Design for Table-Spoons, invented by BERNHARD D. BEIDERHASE, of New York, N. Y.

The nature of my invention is fully represented in the accompanying drawing, to which reference is made.

Figure 1 is a front or fair view of the spoon. Fig. 2 is a view of the reverse side. Fig. 3 is a cross-section of Fig. 1 on the line $x\ x$. Fig. 4 is a cross-section on the line $y\ y$.

The distinctive features of my design are found in the ornamentation of the sides of the handle, as shown in Figs. 1 and 2.

Having thus described my invention, I claim as new and desire to secure by Letters Patent—

The above design as characterized by the ornamentation of the handle, substantially as shown.

BERNHARD D. BEIDERHASE.
